UNITED STATES PATENT OFFICE.

WILLIAM L. BLISS, OF NIAGARA FALLS, NEW YORK, ASSIGNOR, BY MESNE ASSIGNMENTS, TO U. S. LIGHT & HEAT CORPORATION, OF NIAGARA FALLS, NEW YORK, A CORPORATION OF NEW YORK.

TERMINAL BOX.

1,191,060.

Specification of Letters Patent.

Patented July 11, 1916.

Application filed May 4, 1912. Serial No. 695,057.

To all whom it may concern:

Be it known that I, WILLIAM L. BLISS, a citizen of the United States, residing at Niagara Falls, in the county of Niagara and 5 State of New York, have invented new and useful Improvements in Terminal Boxes, of which the following is a full, clear, concise, and exact description, reference being had to the accompanying drawing, forming a 10 part of this specification.

My invention relates to improvements in terminal boxes.

Among the objects of my invention I aim to provide an improved terminal box which 15 may be secured directly to a generator.

In the accompanying drawings I have illustrated one form of my invention adapted particularly for use in connection with a car lighting generator having a reversible 20 and removable brush mechanism, although not limited to such use.

The invention may, of course, assume other forms.

The views of the drawings are as follows: 25 Figure 1 is an elevation of the preferred form of terminal box, showing the same mounted directly on a car lighting generator. Fig. 2 is an enlarged elevation of the terminal box with the cover removed. Fig. 30 3 is a sectional view taken on the line 3—3 of Fig. 2. Fig. 4 is a sectional elevation taken on the line 4—4 of Fig. 2. Fig. 5 is a perspective view of the insulating block which is mounted within the terminal box.

35 The junction box is shown as being secured directly to the casing or field frame of a car lighting generator 1, which is adapted to be suitably supported beyond the end of a car truck in order that the armature may be driven by a belt connection from one of the car axles. The junction box comprises the receptacle 2 and the cover 3 removably secured thereto by means of studs 4. The receptacle 2 or main body portion 40

45 is provided with side walls or flanges 5 completely surrounding the same and extending beyond the base of the receptacle and terminating in a curved outline adapted to fit against the circular exterior of the 50 generator field frame, as clearly shown in Fig. 4. The cover 3 is also provided with inclosing flanges or side walls 6 adapted to rest on the flanges 5, which have a contour similar to the contour of the flanges 6. The 55 cover is guided to its proper position, when

it is being placed over the main receptacle, by means of projecting lugs 7 adapted to receive the studs 4. When the receptacle and cover are clamped together, as shown in Fig. 4, an outlet or opening is provided in 60 the lower end of said box by the meeting of the semi-cylindrical extensions 8 carried by the receptacle and the cover respectively.

The junction box is bolted to the generator field frame preferably by means of 65 bolts 9 made of suitable conducting material. I preferably employ four brass bolts for this purpose, each of which is adapted to be connected as part of a circuit, as hereinafter explained. Each bolt is incased in 70 an insulating tube or lining 10, where it passes through the wall of the generator field frame 1, and is further insulated therefrom by the common insulating block or 75 strip 11, having therein a plurality of recesses or slots 12 preferably equal in number to the number of bolts. The heads of the bolts are received in these slots and are thereby prevented from turning, as will be clearly apparent from an inspection of Fig. 80 3. The inner ends of the bolts pass through an insulating block 13 constructed preferably of hard wood which has been treated with a paraffin bath. A plurality of elongated rivets 14 are preferably run through 85 the block to reinforce the same. A number of reinforcing plates 15, preferably equal in number to the number of bolts 9, are suitably secured to the inner face of the block 13. These plates have marked thereon suitable 90 symbols to assist the operator in making the proper terminal connections. The block is provided with a lower ridge 16 having preferably four recesses 17 cut therein in line with the plates 15. The block also 95 has recesses 18 in its rear face, which permit the insulating tubes 10 to project a safe distance beyond the outer surface of the generator field frame.

The terminal members 19 are carried by 100 the bolts 9 and are clamped thereto in good conducting relation therewith. The small nuts 20 when tightened firmly clamp the main portion of the terminal box 1 against the generator field frame. The additional nuts 21, when tightened up, firmly clamp 105 the terminal members 19 between the nuts 20 and 21. Each terminal member 19, of which there are preferably three, arranged as shown in Fig. 2, comprises preferably a 110

brass tube having a flattened end clamped in the manner described. The cylindrical ends of these terminal members are received within the recesses 17 and are adapted to receive the ends of three conductors (not shown) which conductors pass through the opening formed by the extensions 8, and extend from the terminal box to some point on the car body adjacent the car truck.

10 As shown in Fig. 2, the left-hand terminal member 19 is clamped in conducting relation with the plate marked “—G.” This indicates the negative generator terminal, or, in other words, the negative brushes on the 15 commutator. A conducting strap 22 connects the left-hand bolts, as is shown clearly in Figs. 2 and 3. Accordingly, the circuit divides at this point, one branch of the circuit extending through the left-hand bolt 9, 20 and another branch through the bolt 9 immediately adjacent thereto.

Referring to Fig. 3: It will be seen that an additional conducting strap 23 is clamped beneath the head of the left-hand bolt, and 25 is also clamped in firm engagement with the bifurcated terminal 24 of a flexible conductor 25 by means of a bolt 26 having a nut at the other end 27 provided with a handle or wrench 28, whereby the head of the bolt 30 may be drawn inwardly to firmly clamp the parts mentioned. One end of the strap 23 is secured preferably by a small screw 29, the head of which is adapted to project into an opening 30 in the terminal 24, and there- 35 by positively lock said terminal in position. It is apparent that when the handle 28 is revolved in a direction to loosen the nut 27 from the bolt 26 the terminal 24 may be readily lifted from the head of the screw 40 and withdrawn entirely from beneath the head of the bolt 26.

The head of each bolt 9 is provided with a recess 31. This recess in the case of the 45 three right hand bolts shown in Fig. 3, is intended for the reception of the bared end of the insulated conductors, which ends may be soldered therein. As indicated in Fig. 2, the —F and +F conductors lead to the field windings and the +G conductor leads to the 50 positive brushes. It will be seen as viewed in Fig. 3, that the opening 31 of the negative field terminal opens downwardly. The opening for the positive field terminal is upward and the opening of the positive brush terminal is to the right. This permits the conductors to be led off in the desired direction without unnecessary bending. The connection or disconnection of these conductors is facilitated by removing the encircling 55 band or cover 32 which covers certain openings through which the brushes are readily accessible.

From the above description it will be 60 seen that the terminal box is conveniently located on the outside of the generator

frame in a position where it is readily accessible by simply removing the cover of said terminal box. The terminal connections are exposed to view, said connections being plainly marked in such a manner that an improper connection is very unlikely to occur. 70

I do not limit myself to the details shown and described, as various changes may be made therein and in the combinations thereof without departing from the spirit of the 75 invention.

What I claim as new and desire to secure by Letters Patent of the United States is:

1. In combination, a terminal box, a support therefor, a plurality of bolts passing 80 through one of the walls of said terminal box for securing said terminal box to said support, said bolts also serving as branch circuit conductors.

2. In combination, a receptacle, an insulating member within said receptacle, a plurality of terminals on said insulating member, and a plurality of bolts serving as branch circuit conductors and to secure said receptacle to a support, said bolts passing 85 through said insulating member and serving to clamp said terminals and to secure said receptacle to said support. 90

3. In combination, a generator provided with an inclosing casing, a terminal box for 95 said generator, said box having terminal members passing through said generator casing and serving also to hold said box in position, generator conductors within said casing, and means for detachably connecting said terminals and generator conductors within said casing, said means being operable from the outside of said generator casing. 100

4. In combination, a support, a terminal 105 box attached to the front end of said support, conducting members extending from said box through said support, conductors on the rear of said support, and means for detachably connecting said conductors and 110 conducting members, said means being operable from the front of said support.

5. In combination, a terminal box, a generator field frame, a plurality of bolts for securing said box to said frame, said 115 bolts being arranged with their heads within said field frame and having openings in said heads to receive conductors, said bolts serving also as branch circuit conductors leading from the outside to the inside of 120 said generator field frame.

6. In combination, a generator provided with a casing, a terminal box, a plurality of bolts for clamping said terminal box to said casing, said bolts also serving as 125 branch circuit conductors.

7. A detachable terminal connector, comprising a clamping bolt passing through a support, a bifurcated conductor terminal adapted to straddle said bolt, a conducting 130

- element having an opening therein for said bolt, and a projection extending into an opening in said conductor terminal when the same is clamped between the head of 5 said bolt and the head of said conducting element, and means operable from the side of said support opposite said terminal for causing said bolt to clamp the conductor terminal and conducting element together, 10 thereby positively locking the parts against separation.
8. In combination, a terminal box, a generator field frame on which said box is adapted to be mounted, a strip of insulating 15 material on the opposite side of said generator field frame, and conducting bolts passing through said field frame and clamping said insulating material and said terminal box against the wall of said generator field frame, whereby circuit connections may be 20 established from conductors in said terminal box to conductors within the generator

field frame, the heads of said conducting bolts fitting within recesses in said insulating material to lock said bolts against turning. 25

9. In a terminal box, a block of insulating material, said block being clamped against the base of said terminal box, a plurality of conducting plates mounted on the upper 30 face of said block, and a circuit terminal clamped against each of said plates, said block having a ridge along one side thereof and a plurality of notches in said ridge, each of said circuit terminals being received 35 within one of said notches.

In witness whereof, I have hereunto subscribed my name in the presence of two witnesses.

WILLIAM L. BLISS.
